UNITED STATES PATENT OFFICE.

ARTHUR BENGMAN JONES, OF LINCOLN, MASSACHUSETTS.

SEAT-COVER.

SPECIFICATION forming part of Letters Patent No. 663,279, dated December 4, 1900.

Application filed January 4, 1900. Serial No. 346. (No model.)

To all whom it may concern:

Be it known that I, ARTHUR BENGMAN JONES, a citizen of the United States, and a resident of Lincoln, in the county of Middlesex and State of Massachusetts, have invented 5 a new and Improved Seat-Cover, of which the following is a full, clear, and exact description.

The object of the invention is to provide a 10 new and improved seat-cover which is simple and durable in construction, more especially designed for use on single seats—such as are employed on mowers, reapers, and other agricultural machines and vehicles—and arranged to permit of convenient attachment to a seat and to be quickly folded or extended, 15 as desired by the operator.

The invention consists of novel features 20 and parts and combinations of the same, as will be fully described hereinafter and then pointed out in the claims.

A practical embodiment of my invention is represented in the accompanying drawings, 25 forming a part of this specification, in which similar characters of reference indicate corresponding parts in all the views.

Figure 1 is a sectional side elevation of the improvement on the line 1 1 in Fig. 2. Fig. 2 is a front view of the same. Fig. 3 is a sectional side elevation of the same folded up, 30 and Fig. 4 is a sectional plan view of the same on the line 4 4 in Fig. 1.

The improved seat-cover consists, essentially, of a frame A, adapted to be secured to 35 a seat B and arranged to support at its upper end a top C. The frame A is provided with a standard D, mounted to slide vertically in a bearing E', formed or secured on a base E, preferably made segmental and provided at its inner face with a lining E² of 40 leather, rubber, or other suitable material, fitting the outside curvature of the back of the seat B, as is plainly indicated in the drawings. Hook-bolts E³ extend from the 45 base E to engage the seat and securely fasten the base in place on the seat, as is plainly shown in the drawings. The base E is also provided with upwardly-extending braces E⁴, carrying at their junction a clamping-bolt E⁵, 50 extending through a vertically-disposed slot D', formed in the standard D to permit of moving the standard D up or down in its

bearing E' and to securely fasten the standard in position by the clamping-bolt E⁵ after the desired adjustment has been made. The 55 bolt E⁵ is preferably provided with a handled nut, as plainly shown in the drawings.

On the upper end of the standard D is bolted or otherwise secured a U-shaped arm F, also connected by braces F' with the standard D, and from said braces F' extend downwardly-adjustable straps G, connected with the seat B at the sides thereof, so as to assist in securely holding the standard in position on the seat B and at the same time 65 forming a back for the operator to lean against when occupying the seat B. It is understood that the straps G are lengthened or shortened according to the up or down adjustment of the standard D. 70

In the forward ends of the arm F are held pivots H in the form of clamping-bolts, on which are fulcrumed the side arms I' of the main bow I for the top C, said bow I extending rearwardly at an obtuse angle from the 75 side arms I', as is plainly shown in Fig. 1. On the side arms I' are formed forwardly-extending branch arms I², on which are fulcrumed the ends of the front auxiliary bow J, and on the upper ends of the side arms I' 80 are fulcrumed the ends of the next auxiliary bow K, intermediate the bows J and I and arranged to stand in a vertical plane when the top is extended, as is plainly indicated in Fig. 1. On the side arms I' are also formed 85 the rearwardly-extending branch arms I³, on which are fulcrumed the ends of the rear or bottom bow L, and on the bows J and L are secured projections J' L', respectively connected with each other by the usual knuckle-braces O for holding the top C in an extended open position, as plainly indicated in Figs. 1 and 2, the brace when closed permitting of swinging the several auxiliary bows toward the main bow I when it is desired to fold the 95 top, as indicated in Fig. 3. When this is to be done, the clamping-bolts forming the pivots H are loosened to allow the main bow I to swing rearwardly, as shown in Fig. 3, so that the entire top is swung rearward and 100 downward into a folded position, as shown in the said Fig. 3.

Over the several bows J, K, I, and L extends a covering N of any suitable fabric

- material, having at its sides straps N' for connection with loops on the arms I' for holding the covering in place, the sides of the covering being also preferably slitted in a vertical direction, as at N², and having a lacing N³ for connecting the sides of the slit with each other to permit of drawing the covering as tight as desired over the several bows J, K, I, and L.
- 10 The clamping-bolts for the pivots H are not sufficient to hold the top C rigidly when extended, and in order to accomplish the desired result I employ a coil-spring P, secured to the standard D near the upper end thereof and connected with the rear bow L at the middle thereof, so that the top C is yieldingly mounted—that is, it can rock slightly on its pivots H, with the spring P as a rest for the rear end of the top. When the top is swung
- 15 into a folded position, the end of the coil-spring P attached to the rear bow L, is carried below the point of attachment of the other end of the spring to the standard, and in this position the spring has a tendency to keep the top folded. The several bows J, K, I, and L are flexibly connected with each other at their middle by a strap Q, connected at its ends by buckles Q' Q² with the bows J and L, respectively.
- 20 The construction above described permits of readily attaching the frame A to the seat B and allows of raising the standard D, and with it the top C, to bring the latter into the desired position relatively to the operator seated on the seat B. The arrangement also permits of conveniently extending or folding the top C and when folded and lowered with the standard D, as shown in Fig. 3, allows perfect freedom to the operator seated on the
- 25 seat B, as the covering N, with the middle portions of the several bows, folds at the rear of the standard, and consequently is not in the way of the operator.
- Having thus fully described my invention, 45 I claim as new and desire to secure by Letters Patent—
1. A seat-cover, comprising a frame, a top pivoted at its sides to the upper end of said frame, and a coil-spring attached at one end to the rear of the top at or near the middle thereof, the other end of said spring being attached to the frame to form a seat for the top to yieldingly hold it in an extended position, as set forth.
- 50 2. A seat-cover, comprising a standard carrying a bow-shaped frame at its upper end, a top hinged at its sides to the ends of the bow-

shaped frame, and a coil-spring connecting the rear of the top to the standard near the upper end thereof, for the purpose set forth. 60

3. A seat-cover frame for supporting a top, comprising a curved base having hook-bolts whereby it may be fastened to a seat and also formed with a vertically-disposed bearing upwardly-extending braces secured to said base 55 and having a clamping-bolt at their junction, and a slotted standard receiving the clamping-bolt in its slot and fitted in the bearing of the base, a frame for the top secured to the upper end of the standard, and having braces 70 connecting it therewith, and adjustable straps arranged to connect the upper end of the standard with the seat, as shown and described.

4. A seat-cover frame for supporting a top, 75 comprising a base adapted to be fastened to the seat, and having a bearing and braces, a standard mounted to slide in said bearing and adapted to be fastened to said braces, a U-shaped arm extending at an angle to the standard and secured to the upper end thereof, to carry pivots for the cover-top, and adjustable straps for connecting the upper ends of said frame with the seat to which the base is to be fastened, substantially as shown and de- 85 scribed.

5. A seat-cover, comprising a standard having a supporting-arm at its upper end, a main bow hinged at its side arms on said supporting-arm, auxiliary bows pivoted to the main 90 bow near the fulcrum end thereof, a knuckle-brace for connecting the forward and rear auxiliary bows with each other, and a coil-spring connecting the rear auxiliary bow with the standard, substantially as shown and de- 95 scribed.

6. A seat-cover, comprising a standard having a supporting-arm at its upper end, a main bow hinged at its side arms on said supporting-arm, auxiliary bows pivoted to the main 100 bow near the fulcrum end thereof, a knuckle-brace for connecting the forward and rear auxiliary bows with each other, and a coil-spring connecting the upper end of said standard with the rear bow at the middle thereof, 105 substantially as shown and described.

In testimony whereof I have signed my name to this specification in the presence of two subscribing witnesses.

ARTHUR BENGMAN JONES.
